United States Patent Office.

JOHN NESTER, OF PORTLAND, OREGON.

Letters Patent No. 97,795, dated December 14, 1869.

IMPROVEMENT IN SCRIBE-HOOK.

The Schedule referred to in these Letters Patent and making part of the same.

To all whom it may concern:

Be it known that I, JOHN NESTER, of Portland, in the county of Multnomah, and State of Oregon, have invented a new and improved Scribe-Hook for Weather-Boarding; and I do hereby declare that the following is a full, clear, and exact description thereof, which will enable others skilled in the art to make and use the same, reference being had to the accompanying drawings, forming part of this specification, in which—

Figure 1 represents a side view, partly in section, of my improved weather-boarding hook.

Figure 2 is a plan view, partly in section, of the same.

Figure 3 is a transverse section of the same, taken on the plane of the line x x , fig. 1.

Similar letters of reference indicate corresponding parts.

This invention relates to certain improvements on the scribe-hook for weather-boards for which Letters Patent No. 72,885 were granted to me on the 31st day of December, 1867.

The present invention has for its object to make the instrument more generally useful, and better adaptable to the purposes for which it is intended, and to provide for an adjustable spur and marker.

The invention consists, first, in attaching the spur to a longitudinal pin or screw, which can be turned, so that the spur may be swung out of the way.

The invention also consists in making the marker adjustable on its fastening-pin, and in providing it with a V-shaped cutting-edge, so that it may swing on said pin, in accordance with the direction in which the slide is moved.

The invention consists, further, in providing springs on the main board-hook, for retaining the slide at either end.

A, in the drawing, represents the body of the tool.

It is made of wood, or other suitable material, lined with metal plates a a , on three or more of its sides, and provided with projecting arms b b at the ends, as shown.

B is the slide-gauge, arranged on the slotted surface of the block A, to serve, in connection with the spur c , to indicate the distance between the several boards.

The slide B, is not, as in the first patent, operated

by a longitudinal screw, but works independent in the slotted part of the block A, and can be locked in any desired position by a thumb-screw, d .

The scale e , on the face of the block A, extends from the spur.

Another ordinary inch-scale, f , is arranged on the same block, to enable the same to be used as a rule.

The spur c projects from a longitudinal pin, g , which can be turned so as to swing the spur out of the way, into a slot provided in the block A.

In case the device is to be used for other purposes than for weather-boarding, the spur is carried out of the way.

The marker D is fitted upon a pin, h , that has a head working in a slot on one side of the block A. The marker is a knife, with a V-shaped cutting-edge.

i is a pin, projecting from the pin h .

The pin i fits through a segmental slot of a plate, j , that is clamped upon the pin h by a nut, k , or otherwise.

The marker is thus at liberty to swing either way, so that its point l will always swing back, when the device is drawn over a surface to be marked.

As soon as the motion of the block A is reversed, the position of the marker will also be changed.

In the block A are arranged springs m m , within the slot in which the pin h travels, and at the ends of such slot, so as to retain the marker at either end, to prevent it from working loose on the block.

Having thus described my invention,

What I claim as new, and desire to secure by Letters Patent, is—

1. The marker D, when provided with the V-shaped cutting-edge, in combination with the pin i , projecting from the pin h into the segmental slot of the plate j , all arranged to operate substantially as herein shown and described, and for the purpose set forth.

2. The springs m m , in combination with the marking-device D h j , for the purpose of retaining the marker, arranged as herein shown and described.

The above specification of my invention, signed by me, this 25th day of May, 1869.

JOHN NESTER.
